UNITED STATES PATENT OFFICE.

PAUL CRICCHIO, OF NEW YORK, N. Y., ASSIGNOR TO ROYAL METAL LIGHTING FIXTURE COMPANY, INC., A CORPORATION OF NEW YORK.

DESIGN FOR A LIGHTING-FIXTURE BRACKET.

Application filed December 9, 1926. Serial No. 19,996. Term of patent 3½ years.

To all whom it may concern:

Be it known that I, PAUL CRICCHIO, a citizen of the United States, and a resident of New York, county of Bronx, and State of New York, have invented a new, original, and ornamental Design for a Lighting-Fixture Bracket, of which the following is a specification, reference being had to the ac-

companying drawing, forming a part hereof.

The figure in the drawings shows a perspective view of the lighting fixture bracket.

I claim:

The ornamental design for a lighting fixture bracket substantially as shown.

PAUL CRICCHIO.
